UNITED STATES PATENT OFFICE.

ARTHUR WHITE, OF SHEBOYGAN FALLS, WISCONSIN.

REINFORCED STRUCTURAL BUILDING-SECTION.

1,067,854.

Specification of Letters Patent. Patented July 22, 1913.

Application filed January 22, 1910. Serial No. 539,454.

To all whom it may concern:

Be it known that I, ARTHUR WHITE, residing in Sheboygan Falls, in the county of Sheboygan and State of Wisconsin, have 5 invented new and useful Improvements in Reinforced Structural Building-Sections, of which the following is a description, reference being had to the accompanying drawings, which are a part of this specification.

10 This invention relates to improvements in reinforced structural building material and more particularly to that class in which buildings are constructed of interlocking building blocks and the floors and roof 15 thereof formed of reinforced sections or slabs of cementitious material shaped to interlock with adjacent sections and also with the vertical walls of the building.

One of the objects of this invention is to 20 provide floor, roof or ceiling building sections formed of cementitious material having longitudinal reinforcing metal bars molded therein which are adapted to be anchored to the vertical walls or partitions of 25 the building of which they form a part.

A further object of the invention is to provide a floor, roof or ceiling building section formed of cementitious material having transverse reinforcing metal strips 30 molded therein which are constructed to be locked to the metal reinforcing strips of adjacent sections.

A further object of the invention is to provide a floor or ceiling building section 35 having longitudinal and transverse reinforcing metal bars and strips molded therein which are rigidly connected together to form all of the reinforcements of the sections into a unitary structure which is anchored to the walls of the building, when 40 assembled together to form a floor or ceiling.

While my improved building sections are particularly adapted for use in constructing 45 floors, roofs and ceilings of buildings, it is also adapted for other uses in which it may be employed with advantage.

With the above, and other objects in view, the invention consists of the structural 50 building section as set forth in the claims and its parts and combinations, and all equivalents thereof.

In the accompanying drawing, in which the same reference characters indicate the 55 same parts in all of the views, Figure 1 is a vertical sectional view of fragments of a

wall and partitions of a building having the improved floor section, the floor sections being in longitudinal section; Fig. 2 is a plan view of several of the sections joined together; parts broken away and other parts in section; Fig. 3 is a transverse sectional view taken on line 3—3 of Fig. 1, of two of the sections joined together; Fig. 4 is a similar view thereof taken on line 4—4 of Fig. 1; Fig. 5 is a transverse sectional view of two sections having modified forms of reinforcing strips; and Fig. 6 is a transverse sectional view of a floor section showing a modified form of connection between the longitudinal rod and the transverse strip.

Referring to the drawings the numeral 10 indicates the outside vertical wall of a building, and 11 the vertical partition wall thereof which are formed of interlocking blocks 12 provided with tongued and grooved portions 13 and 14 respectively.

The floor sections or slabs 15 may be of any desirable size and form found to be 80 desirable in constructing buildings. The body of the sections 15 are formed of any cementitious material that may be molded in a plastic state in the form desired, and when hardened forms a rigid structure 85 adapted to withstand the strain to which it is subjected. The sections of slabs are provided with tongues and grooves 16 and 17 formed on the side edges thereof which are adapted to engage the tongues and 90 grooves of adjacent sections when assembled together to form a wall, roof or ceiling and form substantially water-proof joints. The sections which are adapted to have their ends rest on the outside walls of the building and form part of the wall itself are provided with transverse tongues 18 and 95 grooves 19 positioned to register and engage the tongues and grooves 13 and 14 of the building blocks forming the outside 100 wall to anchor said sections to the walls. Each of these floor sections are provided with one or more reinforcing rods 20 which extend substantially the entire length of the sections and at one end project, in the 105 form of an eye 21, beyond the end to form a means for connecting the ends of two sections together. The ends of these reinforcing rods are positioned near the upper 110 surface of the section and extend downwardly at an incline to the medial portion of the section and near the lower surface

thereof to form a mechanical truss to strengthen and support the material of the section and form a rigid structure. The ends of the sections which are adapted to be connected together are provided with registering recesses 22 to accommodate the projecting eyes of the rods of opposite sections and end pins 23 which extend through said eyes to bind the ends of the sections together and also project a sufficient distance above and below the sections to enter the blocks of the partition wall 11 and anchor the said sections to said partition. The ends of the rods 20 which extend to the exterior ends of the sections 15 are provided with eyes 24 which are embedded in the section and the sections have openings 25 registering therewith in which anchor pins 26 are inserted. These pins extend through the openings and the eyes and project into the building blocks forming the outside wall to serve as additional anchoring means for said sections. The sections 15 are also provided with transverse reinforcing metal strips or bars 27 which are embedded in the sections and are adapted to be connected to the transverse strips of adjacent sections. In the preferred form, the transverse reinforcing strips are each formed of a single strip of metal bent over upon itself with the loop 28 shaped to conform to the tongue 16 of the section and with the ends 29 diverged to conform to the groove 17 of the section. The tongue and grooved portions of the reinforcing strips are shaped to lie flush with the surfaces of the sections forming the tongues and grooves so that smooth connecting surfaces are presented for engagement with each other. Each longitudinal tongue and grooved portion of the strips and of the sections are provided with openings 30 which register with each other when the sections are assembled together for the insertion of locking pins 31 which serve to lock the sections and also the transverse strips together. The two portions of the transverse strips are positioned respectively above and below the longitudinal reinforcing rods and are clamped thereto by means of bolts 32 which pass through openings in said strips alongside of the rods and draw said strips together and clamp the rods therebetween. The upper portion of the strip is bent to form recesses 33 to more securely clamp the rods. The upper portions of the transverse strips positioned adjacent to the exterior ends of the sections are bent upwardly to engage the eyed ends of the longitudinal rods and are fastened thereto by the anchoring pins 26 before mentioned which extend through the eyes of said rods and through openings in the strips. Additional reinforcing strips 34 are provided for the ends which are positioned immediately below the longitudinal rods and

the upwardly bent portions and through which the pins 26 also pass.

In the modified form shown in Fig. 5 the reinforcing transverse strips 35 are of single thicknesses and extend below the longitudinal rods 20 and are not connected thereto. The form shown in Fig. 6 is likewise provided with a single thickness transverse strip and differs from the form shown in Fig. 5 in that only one longitudinal reinforcing rod is shown which is clamped to the transverse rod 36 by means of a bolt 37 having a hooked end which engages the rod.

In some cases the sections will have both ends of similar construction so that a number of sections may be connected together inside of a building or one section may extend from wall to wall and be anchored thereto.

A strip 38 may be used, if desired, to form a tongue covering the joint and in which case the block resting on the joint will be provided with a corresponding groove to engage said tongue and the pins 23 will extend into said strip.

The reinforcing rods and strips are molded in the sections while said sections are in a plastic state.

From the foregoing description, it will be seen that a reinforced structural building section is provided which is strong and durable and when assembled to form a floor or roof or other parts of a building, the sections and their reinforcements are securely locked together in both longitudinal and transverse directions and the sections are also anchored to the walls and partitions to form substantially a unitary structure which will withstand any strain which it may be subjected to.

What I claim as my invention is:

1. A reinforced building section, comprising a body part of cementitious material formed with a tongue on one side edge and a groove in the other side edge, a longitudinally positioned reinforcing bar embedded in the body portion and having eyed ends, one of said ends projecting beyond the body portion, a transversely positioned reinforcing strip embedded in the body portion and having openings provided near the ends thereof, one of said ends forming part of the tongue and the other end forming part of the wall of the grooved portion of the section, and pins extending through the eyes of the bar to anchor the bar to a wall and to connect the bar to the bar of another section and through the openings of the strip to connect said strip to the strips of other sections.

2. A reinforced building section, comprising a body part of cementitious material formed with a tongue on one side edge and a groove in the other side edge, a longitudinally positioned reinforcing bar embedded

in the body portion and having eyed ends, one of said ends projecting beyond the body portion, a transversely positioned reinforcing strip embedded in the body portion and having openings provided near the ends thereof, one of said ends forming part of the tongue and the other end forming part of the wall of the grooved portion of the section, said ends of the transverse strip being positioned to overlap the ends of transverse strips of adjacent sections when placed together, means for connecting the longitudinal bar to the transverse strip, and pins extending through the eyes of the bar to anchor said bar to a wall and to connect said bar to the bar of another section and through the openings of the strip to connect said strip to the strips of other sections.

3. A reinforced building section, comprising a body part of cementitious material formed with a tongue along one lateral edge and a corresponding groove in the opposite edge, a reinforcing bar embedded in the body portion and extending longitudinally at an angle therein and having eyed ends, one of said eyes projecting beyond the end of the section, a reinforcing strip embedded in, and extending transversely across the body portion, said strip extending above and below the longitudinal bar and having a looped end conforming to the shape of and embracing the tongue of the section and the ends of the strip opposite to the tongue portion being diverged to conform to the recess of the groove, said tongue and grooved portions of the body portion provided with openings registering with openings provided in the strip, means for clamping the two portions of the strip together to bind it to the longitudinal bar, and pins extending through the eyes of the bar and through the openings of the strip to anchor and connect the section to other parts of a building.

4. A reinforced building section, comprising a body part of cementitious material having a tongue formed on one lateral edge and a groove in the other edge, a reinforcing bar embedded in the body part and extending longitudinally at an angle therein and having eyed ends, one of said eyed ends projecting beyond the end of the body portion and the other eyed end positioned near the opposite end with the eye registering with an opening extending through the cementitious material, a reinforcing strip embedded in, and extending transversely across the body portion, said strip extending above and below the longitudinal bar and having a looped end conforming to the shape of and embracing the tongue of the section and the ends of the strip opposite to the tongue portion being diverged to conform to the walls of the groove, said tongue and grooved portions of the body portion provided with openings registering with openings provided

in the strip, bolts for clamping the two portions of the strip together to bind it to the longitudinal bar, another reinforcing strip embedded in and extending transversely across the body portion near its end, 70 said strip extending above and below the eye of the longitudinal bar and having opening in register with said eye and also having a looped end conforming to the shape of and embracing the tongue of the section and the 75 ends of the section opposite to the tongued portion being diverged to conform to the walls of the groove, said tongue and grooved portions of the body portion provided with openings registering with openings provided 80 in the strip, a pin extending through the eye of the bar and the opening in the last mentioned strip and projecting below the section to anchor it to a wall, and other pins extending through the other eye of the bar and 85 through the openings of the first mentioned strip to connect the sections to other parts of a building.

5. A reinforcing strip for a building section, comprising a strip of metal doubled 90 over upon itself and looped to form a tongue portion at one end and the doubled over portions diverged at the opposite end to form a groove portion adapted to receive the tongue of an adjacent like strip, said strip provided 95 with openings for the insertion of pins to connect adjacent sections together.

6. A reinforced building section, comprising a body part of cementitious material formed with a tongue on one side edge and 100 a groove in the other side edge and also formed with a tongue and a groove positioned on opposite faces and extending transversely across the section near one end, a longitudinally positioned reinforcing bar 105 embedded in the body portion and having eyed ends, one of said ends projecting beyond the body portion, a transversely positioned reinforcing strip embedded in the body portion and having 110 openings provided near the ends thereof, one of said ends forming part of the tongue and the other end forming part of the wall of the grooved portion of the section, the pins extending through the eyes of the bar to 115 anchor the bar to a wall and to connect the bar to the bar of another section and through the openings of the strip to connect said strip to the strips of other sections.

7. A reinforced building section, comprising a body part of cementitious material, a longitudinally positioned reinforcing bar embedded in the body part and having eyed ends, one of said ends projecting beyond the body portion, a transversely positioned reinforcing strip embedded in the body part and having openings provided in the ends thereof, one of the ends of said strip projecting beyond the main portion of the body part, and pins extending through the eyes 125 130

of the bar to anchor the bar to a wall and to connect the bar to the bar of another section and through the openings of the strip to connect said strip to the strips of other sections, one of said pins extending through the section to anchor the section to a partition.

In testimony whereof, I affix my signature, in presence of two witnesses.

ARTHUR WHITE.
